UNITED STATES PATENT OFFICE.

VIRGINIA H. LOFLIN, OF CENTERVILLE, MARYLAND.

IRONING-BOARD STAND.

1,272,471.

Specification of Letters Patent. Patented July 16, 1918.

Application filed August 27, 1917. Serial No. 188,398.

To all whom it may concern:

Be it known that I, VIRGINIA H. LOFLIN, a citizen of the United States, residing at Centerville, in the county of Queen Anne 5 and State of Maryland, have invented certain new and useful Improvements in Ironing-Board Stands, of which the following is a specification.

This invention relates to improvements in 10 supports for ironing boards, and has for one of its objects to provide a simply constructed device which may be readily moved from place to place and folded into relatively small space when not required or for shipment or storage.

With these and other objects in view, the 15 invention consists in certain novel features of construction, as hereinafter shown and described and then specifically pointed out 20 in the claims; and in the drawings illustrative of the preferred embodiment of the invention—

Figure 1 is a side elevation of the improved device in its preferred form;

25 Fig. 2 is a front elevation of the parts shown in Fig. 1;

Fig. 3 is a detached perspective view of the supporting bracket;

30 Fig. 4 is a perspective view of a portion of the head end of the form of ironing board shown in Figs. 1 and 2.

Fig. 5 is a view similar to Fig. 4 illustrating a modification in the form of the larger end of the board;

35 Fig. 6 is a view similar to Fig. 1 illustrating a modification in the construction;

Fig. 7 is a front elevation of the modified structure illustrated in Fig. 6;

40 Fig. 8 is a perspective view of the "head" end of the form of ironing board shown in Figs. 6 and 7.

Corresponding and like parts are referred to in the following description and indicated in all the views of the drawings by the 45 same reference characters.

The improved device comprises in general a supporting standard, and one or more brackets hingedly supported upon the standard and adapted to be folded into relatively 50 close relation to the standard when not in use or when the device is to be shipped or stored.

The standard may be of any suitable material or construction, and it is not desired, 55 therefore, to limit the invention in this respect. For the purpose of illustration the

standard is shown in Figs. 1 and 2 formed of rods or heavy wires, and in Figs. 6 and 7 the standard is shown formed of a single section of wood. 60

When constructed of metal the forms shown in Figs. 1 and 2 will be employed and comprises body members 10 united at their upper ends as shown at 11, and extended laterally at the lower ends as shown 65 at 12, the lateral extensions being preferably widened at their free ends as illustrated at 13 in Fig. 2 to increase the stability of the standard. By this arrangement the body portion 10 of the standard will be supported 70 firmly in vertical position. If required the portions 10—12 will be further supported by diagonal braces 14. At points corresponding substantially to the points where the ironing board, represented conventionally at 15, is connected, the side members 10 of the standard are bent into eyes or loops 75 16 to receive a transverse bolt 17. Preferably another pair of the eyes will be formed in the side portions 10 of the standard as 80 represented at 18, to receive a holding bolt 19, the latter bolt adapted to support a swinging bracket device for maintaining a sleeve board in position, as hereafter explained. 85

46 Inturned projections 20—21 are carried by the members 10 of the standard above the eyes 16—18, to assist in holding the ironing board and the sleeve board from lateral and longitudinal displacement, as hereafter 90 explained.

When the rod or wire form of standard is employed as shown in Figs. 1 and 2, it may be necessary to couple the members 10 by a metal band 22, to not only hold the side 95 members from displacement, but to form a base against which the brace portion of the lower bracket bears.

The main bracket device is formed from a single section of wire and initially bent 100 into substantially U-shape as shown in Fig. 3, and includes spaced side portions 23 and an end portion 24. The side portions 23 terminate in eyes 25 bearing upon opposite sides of the eyes 16 and through which the 105 bolt 17 passes. The bracket device is thus swingingly coupled to the standard members 10. Intermediate their ends the side portions 23 of the bracket are bent into downwardly directed loops 26 which bear 110 when the bracket is in its substantially horizontal position against the supporting plate

or web 22, as shown in Figs. 1 and 2. By this means the loops 26 serve as braces to support the body portion of the bracket substantially in horizontal position. When not in use the bracket device is folded against the upper portions of the side members 10 of the standard and engage beneath a suitable catch 27 connected to the transverse portion 11 of the standard.

When the construction of standard shown in Figs. 1 and 2 is employed the larger end of the board 15 is reduced as shown in Fig. 4, the reduced portion entering the space between the sides 10 of the standard and provided with seats or recesses 28 to receive the projections 20, the reduced portion, the recesses 28 and the projections 20 thus coöperating to prevent lateral and longitudinal displacement of the board. The board rests by gravity upon the bracket and requires no other fastening device except the bracket and the projections 20.

The sleeve board is represented conventionally at 29 and is reduced at the larger end and the reduced portion provided with notches like the notches 28 of the main board 15 to receive the projection 21 when disposed in position relative to the standard. The bracket for supporting the sleeve board is represented in Fig. 1, and comprises side portions 30 having projecting portions 31, the latter bearing upon the upper face of the main board 15 as shown in Fig. 6, and thus supports the sleeve board in horizontal position, or in parallel relation to the main board 15.

When the standard is constructed of wood as shown at 32 in Figs. 6 and 7, the bolts 17 and 19 are passed transversely through the standard, and the latter guarded or protected by sheet metal plates 33-34 where the bolts pass through the standard, to protect the latter and prevent the bolt from splitting the standard. The sleeve board supporting bracket is formed with eyes 35 to receive the bolt 19 as shown.

When the construction of standard shown in Figs. 6 and 7 is employed, the larger end of the board 15 will preferably be constructed as shown in Fig. 8 with sockets 40 formed in plates 41 attached to the board 15, the sockets designed to receive the downturned ends 42 of bolts 43, attached to the standard 32.

The bolts and sockets coact to hold the board from displacement in all directions.

At its lower end the standard 32 is received in a suitable support comprising a socket 36 to which it is bolted or otherwise secured as shown at 37. The socket 36 is provided with laterally directed feet 38 and a longer foot or brace member 39 which

performs the same function as the extended portion 12 of the form of standard shown in Figs. 1 and 2, and effectually supports the standard from displacement when the boards 15-29 are connected thereto. Hooks or pegs 40 may be attached to the standard to support various utensils or garments, thus enabling the device to be employed as a supporting rack when not in use as an ironing stand support.

The improved device is simple in construction, can be inexpensively manufactured and moved from place to place as required, and folded into small space when not required or when being shipped or stored.

Having thus described the invention, what is claimed as new is:

1. A device of the class described comprising a standard including side members in spaced relation and with bearings in transverse alignment, each side member having a lateral projection, a bracket device having bearings swingingly engaging the bearings of the standard, means for maintaining said bracket substantially in horizontal position relative to the standard, and an ironing board having a portion engaging said standard members and provided with upwardly opening seats to receive said projections and maintain the board from lateral or vertical displacement.

2. A device of the class described comprising a supporting standard, and a bracket device formed from a single length of wire bent substantially into U-shape and swingingly coupled to the standard, the side members of the bracket being bent into downwardly directed loops to engage the standard and support the bracket at right angles thereto, an ironing board bearing upon the bracket, and means for holding the ironing board from lateral and longitudinal displacement.

3. A device of the class described comprising a supporting standard including vertical side members in spaced relation, a bracket device swinging from said standard and having means for maintaining the body of the bracket at right angles to the vertical axis of the standard, inturned projections carried by the side members, and an ironing board resting upon the bracket device and reduced to engage between the side members, said reduced portions having upwardly opening seats to receive said projections to permit the removal of the board, and maintain the same from lateral or vertical displacement.

In testimony whereof I affix my signature.

VIRGINIA H. LOFLIN. [L. S.]
